UNITED STATES PATENT OFFICE

163,733

PUPPET

Lorraine F. Alexander, Chicago, Ill.

Application April 10, 1950, Serial No. 9,087

Term of patent 3½ years

(Cl. D34—2)

To all whom it may concern:

Be it known that I, Lorraine F. Alexander, a citizen of the United States and a resident of the city of Chicago, county of Cook, State of Illinois, have invented a new, original, and ornamental Design for Puppet, of which the following is a specification, reference being had to the accompanying drawing, forming a part thereof, in which:

I claim:

The ornamental design for a puppet, substantially as shown.

LORRAINE F. ALEXANDER.
